UNITED STATES PATENT OFFICE.

RICHARD H. ECKHARDT, OF YORKTOWN, TEXAS.

OIL-BURNER.

1,063,786.

Specification of Letters Patent.

Patented June 3, 1913.

Application filed July 3, 1912. Serial No. 707,486.

To all whom it may concern:

Be it known that I, RICHARD H. ECKHARDT, a citizen of the United States, and a resident of Yorktown, in the county of De Witt and State of Texas, have invented a new and Improved Oil-Burner, of which the following is a full, clear, and exact description.

The object of the invention is to provide 10 a new and improved oil burner arranged to insure the formation of a thorough mixture of oil, air and a fluid under pressure, such as steam or compressed air, and to prevent flooding of the burner with surplus oil. For 15 the purpose mentioned, use is made of a mixing chamber, a spraying device discharging into the said mixing chamber at the rear end thereof, an air inlet leading to the mixing chamber, and a suction device in front 20 of the mixing chamber for drawing the mixture out of the mixing chamber and forcing it to the burner.

A practical embodiment of the invention is represented in the accompanying drawing, 25 forming a part of this specification in which the figure is a longitudinal section of the oil burner, parts being in elevation.

A mixing chamber A, preferably in the form of a short tube, is connected at the rear 30 end with a fresh air supply pipe B having an inlet C at the bottom which also serves as an outflow for surplus oil that may accumulate in the mixing chamber A and the pipe B. The rear end of the air supply pipe 35 B is closed by a plug D in which is screwed or otherwise secured a fluid pressure pipe E terminating at its forward end in a nozzle E' extending into the rear end of the mixing chamber A. Within the nozzle E' is 40 arranged a nozzle F' of an oil supply pipe F extending through the fluid pressure pipe E and connected with a suitable source of oil supply. A valve G is arranged in the oil supply pipe F to control the amount of oil 45 passing through the same to be atomized by the fluid under pressure passing through the pipe E and its nozzle E', and which fluid under pressure may be steam, compressed air or the like. The fluid pressure pipe E 50 is provided with a valve H to permit of regulating the amount of steam or compressed air passing through the pipe E, and the valve H is connected by a branch pipe I with a fluid pressure supply pipe J connected 55 with a boiler or compressed air reservoir or

the like for supplying the pipe J with steam, compressed air or other fluid.

The forward end of the mixing chamber A is connected with a suction chamber K from which extends a burner tube L for 60 conducting the mixture of oil, air, steam or compressed air to the burner to be burned. Within the suction chamber K is arranged a suction nozzle N extending forwardly and terminating adjacent the beginning end of 65 the burner tube L, and the nozzle N is secured to a pipe N' held in a cap K' attached to the bottom of the chamber K. The outer end of the pipe N' is provided with a valve O connected by a branch pipe 70 I' with the fluid pressure supply pipe J so that fluid under pressure can pass by way of the branch pipe I', valve O and pipe N' to the nozzle N and out of the same to produce a suction in the suction chamber K 75 and consequently in the forward end of the mixing chamber A to draw the combustible mixture forward through the suction chamber J and force the same through the burner pipe L to the burner to be burned thereon. 80

When the oil burner is in use and the valves G, H and O are open then free air is drawn through the inlet C and pipe B into the mixing chamber A, and at the same time the oil is sprayed by the action of the 85 fluid under pressure passing through the pipe E and the nozzle E' at the nozzle F' of the oil pipe F. The sprayed oil mixes with the free air drawn in through the inlet C and the pipe B, and the mixture is 90 drawn forward into the suction chamber K by the action of the fluid passing through the forwardly-extending nozzle N, so that a further intimate mixture of the oil, air, steam or compressed air takes place to provide a highly combustible mixture, which 95 when burned insures complete combustion.

The oil burner shown and described is very simple and durable in construction and is not liable to be flooded as any oil that is 100 not sprayed and passes into the mixing chamber A can readily flow through the pipe B and inlet C out of the burner.

Having thus described my invention, I claim as new and desire to secure by Letters Patent:

1. An oil burner comprising a mixing chamber, an air inlet connected with the rear end of the mixing chamber, a spraying device connected with an oil supply and 110

with a source for supplying fluid under pressure and discharging into the rear end of the said mixing chamber, a suction chamber, a nozzle projecting into the suction chamber in front of the said mixing chamber and connected with the said source of fluid under pressure, and a burner pipe extending from the said suction chamber.

2. An oil burner comprising a mixing chamber, an air inlet connected with the rear end of the said mixing chamber, an oil supply pipe, a pipe for supplying fluid under pressure surrounding the said oil pipe and forming with the latter a spraying device discharging into the rear end of the said mixing chamber, a suction chamber connected with the front end of the said mixing chamber, a suction nozzle extending forwardly in the said suction chamber, a pipe for supplying fluid under pressure connected with the said nozzle, and a burner pipe extending forwardly from the said suction chamber.
3. An oil burner comprising a mixing

chamber, an air inlet connected with the rear end of the said mixing chamber, an oil supply pipe, a pipe for supplying fluid under pressure surrounding the said oil pipe and forming with the latter a spraying device discharging into the rear end of the said mixing chamber, a suction chamber connected with the front end of the said mixing chamber, a suction nozzle extending forwardly in the said suction chamber, a pipe for supplying fluid under pressure connected with the said nozzle, and a burner pipe extending forwardly from the said suction chamber, a pipe connected with a source of fluid under pressure and with the said fluid under pressure pipes, and valves in the said fluid under pressure pipes.

In testimony whereof I have signed my name to this specification in the presence of two subscribing witnesses.

RICHARD H. ECKHARDT.
